UNITED STATES PATENT OFFICE.

CARL LUCKE, OF NEW YORK, N. Y., ASSIGNOR TO LUCKE D'ALIX, OF BROOKLYN,
NEW YORK.

MATRIX.

1,090,787.

Specification of Letters Patent. Patented Mar. 17, 1914.

Application filed May 6, 1908. Serial No. 431,253.

To all whom it may concern:

Be it known that I, CARL LUCKE, a citizen of the United States, residing in the borough of Brooklyn, city and State of New York, have invented new and useful Improvements in Matrices, of which the following is a specification.

The invention relates to matrices for composing machines, and in certain features thereof more particularly to matrices for casting machines which cast a line bar, or linotype, from a plurality of assembled matrices.

Objects of the invention are to provide a matrix which makes possible a composing or casting machine of exceedingly simple construction and also makes possible a machine of small size, and which furthermore has large output capacity and which may employ a great variety of styles and faces without change or shifting of magazines and without a plurality of matrix fonts; to provide further and more particularly for greatly increasing the magazine capacity without a corresponding increase in its size and without duplicating or rendering complex its parts and mechanisms; also to provide a matrix which renders possible exceedingly simple line handling mechanisms and further making possible great simplicity in the general mechanism and structure of the entire casting or composing machine.

These and other objects of invention will in part be obvious and will in part more fully appear hereinafter.

The accompanying drawings, referred to herein and forming a part hereof, illustrate one embodiment of the invention, the same serving in connection with the description herein to explain the principles of the invention.

Of the drawings: Figure 1 illustrates face and side views of a matrix constructed in accordance with the principles of the invention; Fig. 2 illustrates both faces and a side of a matrix constructed in accordance with the principles of the invention; Fig. 3 is a perspective view of a group or line of matrices so constructed.

Referring to the accompanying drawings, illustrating by way of example an embodiment of the invention, there are shown upon the face 2 of the matrix 1 two duplicate characters 3 and 4, said characters standing in

opposite directions, that is, when one character is in the upright position the other character is in the inverted position. Said two characters are duplicates not only in that they represent the same letter but that they are also of the same font and face. In this embodiment said characters are also shown symmetrically arranged along said face, that is to say, if the matrix were placed in the line handling mechanism of a casting machine upon one end with one of said characters in alinement with the mold slot or other casting device and then the matrix were inverted, or stood upon the opposite end, the other character would then be in the same relation to the mold or casting devices. In other words, the matrix could be run into the line with either end up indifferently and the same character of the same font and face could be cast therefrom by one mold or other casting device without moving its position.

The invention, in certain of its aspects, contemplates further providing for more than two characters upon one face of a matrix, each character being in such case a duplicate of another character thereon but standing in opposite directions with respect thereto. In one of its features, furthermore, the invention contemplates having the two characters of each such duplicate pair arranged symmetrically with respect to each other in the sense hereinbefore stated. These features of invention may be combined in a single embodiment and are so shown in the drawings. Referring then to Figs. 2 and 3 of the drawings the matrix 5 is shown having upon one face thereof the characters 6 and 7 which are duplicates, are symmetrically arranged and also stand or foot in opposite directions. There are also shown on said face characters 8 and 9 which are in similar relation with respect to each other as the characters 6 and 7 just described.

The invention, in certain of its aspects, provides a matrix having a plurality of characters upon each of the two opposite faces thereof, each character on a face having its duplicate upon the same face and the characters upon opposite faces being in alinement transversely to the matrix. Certain features of the invention furthermore contemplate in addition to this that the characters of each duplicate pair upon each edge be symmetrically arranged and also

that they stand in opposite directions. These various features are shown combined in a single embodiment and in Fig. 2 of the drawings, upon the opposite face of the matrix 5 from that bearing the characters 6 to 9, are shown characters 10 and 11 bearing to each other of the relations above set forth and likewise characters 12 and 13 also bearing to each other said relations.

- 10 There are also shown in the present embodiment as illustrating one feature of the invention duplicate distributing devices arranged so that either of said devices may coöperate with a single distributer rail or 15 equivalent device depending upon the position in which the matrix is presented thereto. In one aspect of the invention it is contemplated to place these duplicate distributing devices one at each end of the 20 matrix and they are shown at 14 and 15 in the drawings herewith.

In the present embodiment and as carrying out one feature of the invention there are shown on the matrix shoulders 16 which 25 coöperate with suitably shaped parts, either stationary or movable, of the line handling mechanism to accurately position and aline the matrix in casting position. The positioning devices 16 are shown herein at each 30 end of the matrix and said devices at one end of the matrix bear the same relation to one of the characters thereon that the devices at the other end bear to the other of said characters.

35 It will be understood that other features may be employed in connection with a matrix constructed in accordance with the principles of the invention to suit and adapt it for use in a particular composing machine, 40 such as suitable escapement devices and suitable devices for feeding the matrices to the distributer, and so on, or the devices herein described or their equivalents may be employed for such purposes.

45 From the foregoing it will be understood that a matrix has been provided from each face of which a plurality of fonts and faces may be cast and that castings may be made from each face thereof and furthermore 50 that any and all faces and fonts carried by the matrix may be, in an embodiment comprising certain features of the invention, secured from the matrix irrespective of its being distributed into the magazine or let 55 out of the magazine into the assembling devices with either end to.

It may be stated more in detail that by varying the position of the line during casting and by swinging or otherwise moving 60 the magazine with either end into relation with the escapement devices or the distributing devices, as one may choose to consider it, the various faces may be made available and neither the magazine or the matrix 65 has been increased in size nor has the mecha-

nism of the magazine been multiplied or rendered complex. The ability to use the matrix irrespective of whichever end is in a particular position, is of great usefulness furthermore in aiding and simplifying the 70 construction of a casting machine, as well as in decreasing its bulk and realizing the other advantages herein set forth, together with others which will be obvious.

From all the foregoing it will be understood that a matrix has been provided embodying the principles of the invention set forth herein, and realizing the objects of the invention and the advantages herein set forth together with other objects and advantages.

The invention, in its broader aspects, is not limited to the particular construction shown, nor to any particular constructions by which it has been or may be carried into effect, as many changes may be made in the construction without departing from the main principles of the invention and without sacrificing its chief advantages.

What I do claim as my invention and desire to secure by Letters Patent, is:

1. A matrix having a plurality of distributing devices thereon reversely arranged with reference to each other, said matrix also having a character theron in multiplicate and footing in opposite directions, one character bearing the same relation to one of said distributing devices that another of said characters does to another of said distributing devices.

2. A matrix having a plurality of distributing devices thereon and having upon one face thereof a character thereon in multiplicate, one character bearing the same relation to one of said distributing devices that another of said characters does to another of said distributing devices.

3. A matrix having a plurality of distributing devices thereon, one distributing device bearing the same relation to one end of the matrix that another distributing device does to another, and having upon one face thereof a character thereon in multiplicate, one character bearing the same relation to one of said distributing devices that another of said characters does to another of said distributing devices.

4. A matrix having a plurality of alining devices thereon and having upon one face thereof a character thereon in multiplicate and footing in opposite directions, one character bearing the same relation to one of said alining devices that another of said characters does to another of said alining devices all the matrices of the font being 110 of the same length.

5. A matrix having a plurality of alining devices thereon, one alining device bearing the same relation to one end of the matrix that another alining device does to another,

and having upon one face thereof a character thereon in multiplicate and footing in opposite directions, one character bearing the same relation to one of said alining devices that another of said characters does to another of said alining devices all the matrices of the font being of the same length.

6. A matrix having distributing and alining devices in duplicate, one set of said devices having the same relation to one end of the matrix that the other set thereof has to the other end of the matrix, a character in duplicate on said matrix, one of said duplicate characters bearing the same relation to one of said sets of distributing and alining devices that the other of said characters does to the other set of said distributing and alining devices.
7. A matrix having distributing and alining devices in duplicate, one set of said devices having the same relation to one end of the matrix that the other set thereof has to the other end of the matrix, a character in duplicate on one face of said matrix, one of said duplicate characters bearing the same relation to one of said sets of distributing and alining devices that the other of said characters does to the other set of said distributing and alining devices.
8. A matrix having distributing and alining devices in duplicate, one set of said devices having the same relation to one end of the matrix that the other set thereof has to the other end of the matrix, a character in duplicate on one face of said matrix, one of said duplicate characters bearing the same relation to one of said sets of distributing and alining devices that the other of said characters does to the other set of said

distributing and alining devices, and the same character also in duplicate on the opposite face of said matrix from said first-mentioned duplicate characters, one of said duplicate characters on said opposite face 45 being in the same relation to one set of said alining and distributing devices as one of the duplicate characters on said first-mentioned face of the matrix and the other of said characters on said opposite face being 50 in the same relation to the other set of distributing and alining devices as the other duplicate character on said first-mentioned face of the matrix.

9. A matrix having on one face thereof 55 two duplicate characters standing in opposite directions and duplicate distributing devices at each end of the matrix.

10. A matrix having on one face thereof a plurality of duplicate characters standing 60 in opposite directions and on the opposite face thereof, a plurality of other duplicate characters also standing in opposite directions and two duplicate distributing devices carried by said matrix.

11. A matrix having on one face thereof two characters which are duplicates and standing in opposite directions and on the opposite face two characters which are duplicates of each other standing in opposite 70 directions and a distributing device at each end of the matrix.

In testimony whereof, I have signed my name to this specification, in the presence of two subscribing witnesses.

CARL LUCKE.
